METHOD AND APPARATUS FOR MAKING
ELASTIC BANDS

Abraham N. Spanel, Rochester, N. Y.

Application March 20, 1937, Serial No. 132,156

9 Claims. (Cl. 18—41)

This invention relates to endless rubber bands made from latex or the like as well as to the apparatus for and to the method of producing the same.

A feature of the invention relates to a novel form on which one or more endless elastic bands may be made by depositing rubber thereon, integral reinforced edges being generated on the bands during the depositing operation.

A further feature of the invention relates to a novel method of producing endless elastic bands having integrally reinforced edges.

In the drawing,

Fig. 1 is a perspective view of an endless elastic band of the present invention made by the method and on the novel forms herein disclosed.

Figs. 2, 3, 4 and 5 are vertical transverse sections through several bands and illustrate the various types of edge reinforcements obtainable by this invention.

Figs. 6 and 7 are face and edge views respectively of a form on which endless elastic bands having edge reinforcements thereon, may be made.

Fig. 8 is a fragmentary section of the form illustrated in Fig. 6 and taken along line 8—8 thereof.

Fig. 9 is a face view of a modified form on which a single endless band may be made by depositing rubber thereon.

Fig. 10 is a fragmentary section of the form illustrated in Fig. 9, the section being made on line 10—10 of that figure.

The endless elastic rubber band 1 illustrated in Fig. 1 is of substantial width and has integral reinforced margins 2 which may be reinforced in various ways as illustrated in Figs. 2, 3, 4 and 5. The band 1 is adapted to many uses; e. g., it may be used to keep the hair in place during the wearer's participation in strenuous exercises or games; it may be applied over the head and under the chin to support weakened chin muscles and thereby minimize what is commonly known as double-chin; or it may be used to protect the hair when cold creams or cosmetics are applied to the face.

In Fig. 2 there is illustrated the cross-section of a band made on the portion *a* of the form 3 illustrated in Fig. 1. The upper margin of this band is reinforced by a thickened portion 4 at the edge thereof and by a thickened portion or ridge 5 adjacent this edge. The lower margin of this band which has a cut edge 6, is reinforced by a thickened portion 8. The thickened portions 5 and 8 result from the accumulation of rubber, due mainly to surface tension, in the

grooves 23 and 20 in the form. The reinforcement 4, however, results from the accumulation of rubber, by surface tension, adjacent the abrupt shoulder 21 on the form.

In Fig. 3 there is illustrated the cross-section of a band made on portion *b* of the form 3, the margins of the band adjacent the cut edges 6 thereof being reinforced by thickened portions 8 resulting from the accumulation of rubber in the grooves 20 of the form.

In Fig. 4 there is shown the cross-section of a band as generated on portion *c* of the form 3. The upper margin of this band adjacent its cut edge 6 is reinforced by a thickened ridge 8 while the lower edge of this band is reinforced adjacent its thin or torn edge 9 by a thickened reinforcement or ridge 10 which merges into a tapering portion 11. When rubber is deposited on the form 3 it will accumulate in the groove 25 to provide the thickened portion 10. The rubber will also accumulate above the abrupt edge 24 to produce the tapered portion 11.

In Fig. 5, there is represented the cross-section of a band made on the form 12 illustrated in Fig. 9. The upper margin of this band is reinforced by a thickened section 13 resulting from the accumulation of rubber, mainly by surface tension, adjacent the shoulder 28 of the form. The lower margin of the band which terminates in a thin or torn edge 15 is reinforced by a thickened section 14 resulting from the accumulation of rubber in the groove 29.

The form 3 illustrated in Figs. 6, 7 and 8 is capable of making four endless elastic bands at one time, the bands made thereon having reinforced edges 2 integral therewith. This form comprises an elongated flattened body portion 16 having rounded side portions 17 to provide a continuous surface along its horizontal axis. The upper portion 18 of the form is provided with any convenient type of supporting means 19 which are adapted to suspend the form on any suitable dipping or depositing mechanism (not shown).

The body portion 16 of the form is divided into band generating sections *a*, *b*, and *c*, by means of pairs of spaced peripheral grooves 20. While this form has four band-generating sections, it may be designed to make any desired number of bands. The grooves 20 present no abrupt edges but are preferably smoothly rounded as shown in Fig. 8. The upper portion 18 of form projects beyond the body portion 16 to provide an abrupt shoulder 21 terminating in a sharp or abrupt edge 22. There is provided on

the body portion of the form adjacent the abrupt shoulder 21, a substantially smooth-rounded groove 23 similar to the pairs of grooves 20 hereinbefore described. The lower end of the body portion or band generating surface of the form terminates in an abrupt edge 24, while the lower end of the form terminates in a draining fin 26, the purpose of which will hereinafter appear. A smoothly rounded peripheral groove 25, similar to the grooves 20 and 23 is provided in the surface of the form above the edge 24 but in slightly spaced relation thereto.

While the preferred manner of applying a rubber coating to the form, is by dipping the form into a bath of latex, one or more times with a drying interval between dips, it is to be understood that the latex may be applied to the form in any suitable manner such as by spraying, or the like, and if preferred, the acid coagulation method of applying a coating of latex to a form, may be used.

Latex or rubber deposited on the form will be of substantially uniform thickness on the flat surfaces of the form but will accumulate, mainly due to surface tension, in the grooves 20, 23 and 25 and adjacent the abrupt shoulder 21 to generate thickened portions in the layer of rubber on the form. The section in Fig. 8 illustrates the manner in which rubber will accumulate in the rounded grooves 20 to provide thickened reinforcement portions 8. The cross sections of the three types of resulting bands made on the form illustrated in Fig. 6 are clearly illustrated in Figs. 2, 3 and 4. After the rubber has been deposited on the forms, and dried, the layer of excess rubber above the abrupt shoulder 21 may be easily stripped away at the sharp or abrupt edge 22, since that edge will generate a weakened section in the layer of rubber. By grasping the layer of rubber overlying the draining fin 26, the rubber below the abrupt edge 24 may be readily removed since a weakened section in the layer will result at the edge 24. The trimmed layer of rubber remaining on the body portion of the form is next removed from the form. By suitable means, such as cutting dies, the layer of rubber, is severed along the lines 6-6 to form the separate, edge-reinforced bands illustrated in Figs. 2, 3 and 4.

In Fig. 9 there is shown a form 12 on which a single elastic band may be made, said form having a different type of edge reinforcement generating means. The body portion 30 of the form which has an endless surface along its horizontal axis, is provided at its upper end with an abrupt shoulder 28. Rubber will accumulate at this shoulder to generate an edge reinforcement such as shown at 13 in Fig. 5. The lower end of the body portion 30 is made with the peripheral groove 29 therein which is preferably rounded into the main surface of the body portion at its upper side and terminates in the abrupt or sharp edge 31 at the bottom of the body portion. The lower end of the form carries a draining fin 32 while its upper end is provided with any suitable means 19, for supporting the form while dipping and drying the rubber thereon.

The form 12 illustrated in Fig. 9 may be coated with rubber in any suitable manner as by dipping or spraying. The section in Fig. 10 illustrates the manner in which rubber will accumulate adjacent the abrupt shoulder 28 and in the groove 29, of the form 12. After a layer of rubber of suitable thickness has been applied to the form, and dried, the rubber may be separated at the sharp or

abrupt edge 34 adjacent the abrupt shoulder 28 since a line of weakness exists in the rubber layer at this edge. The layer of rubber below the sharp or abrupt edge 31 may be readily separated by grasping the rubber overlying the fin 32 since a weakened section exists in the layer at the sharp edge 31. Fig. 5 shows the cross-section of a band made on form 12.

It is to be understood that the rubber or latex, hereinbefore referred to may be vulcanized prior to the depositing step or the layer of rubber may be vulcanized on the form after the rubber has been deposited thereon; or if preferred it may be vulcanized off the form. By repeatedly dipping and drying the deposited rubber on the form, bands of any suitable or desirable thickness may be obtained.

What I claim is:

1. A form, comprising a body portion on which an endless layer of rubber may be deposited, one end of said body portion terminating in an abrupt overhanging shoulder, the other end thereof terminating in an abrupt edge, said body portion having a peripheral reinforcement-generating groove therein, one side thereof merging into said abrupt edge.

2. The method of making endless edge-reinforced elastic bands, which comprises depositing, on a form, a layer of rubber having alternate wide and narrow band portions of substantially uniform thickness separated by comparatively thick portions, drying said layer, and severing the narrow band portions, to produce bands having thickened portions adjacent at least one of the margins thereof.

3. The method of making endless edge-reinforced bands which comprises depositing, on a form, a layer of rubber having spaced endless band portions, adjacent band portions being integrally joined by a reinforced ring-like section, drying said layer of rubber, and severing said reinforced ring-like section to produce endless bands having at least one edge thereof reinforced.

4. The method of forming endless bands with integral edge reinforcements thereon, which comprises providing a form having an endless band generating surface defined by marginal reinforcement-generating means, dipping said form in a bath of rubber to deposit a layer of rubber of substantially uniform thickness on said band-generating surface and thicker ridges of rubber at said means, drying said layer, and separating the layer to produce a band having integrally reinforced margins.

5. The method of making endless rubber bands which comprises providing a form having spaced pairs of peripheral reinforcement-generating grooves defining band generating surfaces, dipping said form one or more times into a bath of rubber to deposit a layer of rubber thereon having spaced pairs of reinforcements integral therewith and generated by the accumulation of rubber in said grooves, drying the rubber layer, and separating the rubber layer between each pair of reinforcements to obtain endless bands having reinforced edges integral with the bands.

6. The method of making an endless, edge-reinforced band which comprises, depositing on a form, an integral layer of rubber including an endless band-like portion bounded by endless reinforcement sections, drying said layer, separating said layer adjacent said sections to produce an endless band having reinforced edges integral therewith.

7. A form, on which rubber or the like may be deposited to make endless elastic bands with reinforced edges, said form having two opposed flattened surfaces joined by two curved surfaces, 5 said form having pairs of endless reinforcement-generating grooves extending around the same, the grooves of each pair being spaced from each other, said pairs of grooves being spaced from each other, the space between the grooves of 10 each pair being less than the space between adjacent pairs of grooves, the surface of said grooves merging smoothly with the adjacent form surface, the area between adjacent pairs of grooves providing an endless band generating 15 section, whereby bands deposited on said area will be substantially flat in transverse section.

8. A form on which rubber may be deposited to make endless elastic bands with reinforced

edges, said form comprising a body portion having an overhanging shoulder at one end and an abrupt edge at the other end, the body portion having spaced reinforcement-generating grooves therein intermediate said shoulder and abrupt 5 edge dividing said body portion into band-generating sections.

9. A form comprising a body portion on which rubber may be deposited for making endless elastic bands, said body portion having an overhanging shoulder at one end and an abrupt edge at the other end, spaced reinforcement-generating means extending around said body portion intermediate said shoulder and abrupt edge, said means dividing said body portion into endless 10 15 band-generating sections.
